UNITED STATES PATENT OFFICE.

JOSEPH M. HILL AND JOHN C. RENNER, OF CHICAGO, ILLINOIS.

DESIGN FOR A SHOW-CARD HOLDER.

SPECIFICATION forming part of Design No. 28,238, dated February 1, 1898.

Application filed May 8, 1897. Serial No. 635,759. Term of patent 3½ years.

To all whom it may concern:

Be it known that we, JOSEPH M. HILL and JOHN C. RENNER, citizens of the United States, residing at Chicago, in the county of Cook and State of Illinois, have invented and produced a new, original, and useful shape for Show-Card Holders, of which the following is a specification, reference being had to the accompanying drawing, showing a part thereof.

The drawing is a perspective view of a show-card holder of our design.

This show-card holder comprises a gripper having at one side two fingers A A and at the other side the finger B B, opposite the interval between the fingers A A, the material which forms the two fingers being extended in a plane oblique to the plane of the two fingers to afford a rear support for the show-card, the loop which connects the two fingers being crossed by the material thus extended, whereby the show-card may be gripped between the extended material and the loop which crosses the same.

The characteristic features of this design are the form of the fingers A A and B and the terminal E and specifically the shape of the material which forms the parallel fingers A A, which involves the bends a' a' and a³ a³, and the shape of the material which forms the gripper-finger B, which involves a bend at the terminal point of the finger, and coils B' B' in the two branches which extend from the bend, said coils being located at equal distances from such bend.

35

We claim—

The design for a show-card holder herein shown and described.

In witness whereof we have hereunto set our hands at Chicago, Illinois, this 23d day of April, 1897, in the presence of two witnesses.

JOSEPH M. HILL.
JOHN C. RENNER.
